UNITED STATES PATENT OFFICE.

DANIEL S. WAUGH, OF DENVER, COLORADO, ASSIGNOR TO THE ILER ROCK DRILL MANUFACTURING COMPANY, OF DENVER, COLORADO.

SPRAYING ATTACHMENT FOR PERCUSSIVE TOOLS.

No. 889,835.

Specification of Letters Patent.

Patented June 2, 1908.

Application filed July 20, 1906. Serial No. 327,020.

To all whom it may concern:
Be it known that I, DANIEL S. WAUGH, a citizen of the United States, residing at the city and county of Denver and State of Colorado, have invented certain new and useful Improvements in Spraying Attachments for Percussive Tools; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in means for delivering a spray of water at the outer extremity of the drill hole during the drilling operation as where percussive tools are employed to drill holes in rock for blasting purposes. During this drilling operation, the dust escaping at the outer extremity of the hole during the drilling operation is often very annoying especially in case of upholes or those in which the hole is downwardly inclined from its inner to its outer extremity.

The object of my invention is to produce a spray which will allay or arrest the dust under the circumstances aforesaid thus doing away with the annoyance necessarily incident thereto.

In the drawing I have shown the invention in connection with a special construction of drill, but it is evident that it may be employed with tools of widely varying specific construction.

I take a jet of air from the motive fluid supply and bring the same into conjunction with a jet of water, the air and water meeting just before they escape from the spray nozzle which is directed to the outer extremity of the drill hole, whereby a spray is produced which successfully accomplishes the purpose heretofore explained.

Having briefly outlined my improved construction as well as the function it is intended to perform, I will proceed to describe the same in detail reference being made to the accompanying drawing in which is illustrated an embodiment thereof.

In this drawing, Figure 1 is a detail view of my improved spraying apparatus looking in the direction of arrow 1 in Fig. 2. Fig. 2 is a section taken on the line 2—2 Fig. 1.

Fig. 3 is a section taken on the line 3—3 Fig. 2. Fig. 4 is a section taken on the line 4—4 Fig. 2. Fig. 5 is an elevation showing a drill equipped with my improvements, the parts being shown on a greatly reduced scale. 60

The same reference characters indicate the same parts in all the views.

Let the numeral 5 designate the body of a drilling tool; 6 the drill bit connected with the forward extremity of said body; and 7 a crank member through which the motive fluid is delivered to the body or casing of the tool from a suitable source of supply. 65

8 is an air supply conduit which delivers motive fluid to a U-shaped conduit 9 one extremity of which communicates with the hollow crank 7 while the other extremity communicates with a hollow bar 10 in which telescopes a pin 12 upon which the motive fluid acts and forces the said pin against the rock or other surface upon which the tool is mounted. The action of the motive fluid also drives the body of the drill and the drill bit into contact with the breast of the rock or the bottom of the hole where the hole has already been started. This automatic air feed is not novel and nothing is claimed thereon in this application. 70

From the pipe 10, leads a branch pipe 13 its opposite extremity being connected with the chuck of the tool as shown at 14. The spraying mechanism is fastened to this branch pipe 13 and comprises a nozzle 15; a head 16; and a bolt 17, perforated longitudinally to deliver air and water to the head 16. This bolt 17 passes through the head and is provided with passages 18 and 19 respectively. 75

This bolt passes transversely through the branch pipe 13 and the spraying device is clamped to the pipe by means of clamping members 20 and 20 provided with a lining 21 and 22, in order to make a tight joint and securely hold the parts in the assembled relation. The clamping members are tightened upon the pipe by means of a nut 23 applied 80

to the reduced threaded extremity of the bolt and screwed against the clamping member 20. The bolt 17 is provided on the side of the spray head opposite the pipe 13 with nuts 24 and 25, the nut 24 being screwed against 85 the spray head and the nut 25 forming a lock nut. Connected with the threaded extremity of the bolt beyond the lock nut 25, is a coupling sleeve 26 connected with a water delivery pipe 27. The passage 19 opens at the 90

110

right hand extremity of the bolt referring to Fig. 2, and communicates with the water supply conduit 27 at one extremity. The other extremity of the passage 19 communicates with a passage 28 formed in a part 29 projecting laterally from the spray head 16; while the passage 18 reaches from the interior of the pipe 13, and communicates with a passage 30 formed in a projection 31 located on the side of the spray head opposite the projection 29. Threaded into the projections 29 and 31, are adjusting screws 32 which pass through boxes 33 and make a fluid tight joint around the adjusting screws. 10 The inner extremities 34 of these screws are pointed and the fluid is delivered against these points whereby it is finely divided or broken up which facilitates its subsequent action. 15 The inner extremities 34 of these screws are pointed and the fluid is delivered against these points whereby it is finely divided or broken up which facilitates its subsequent action. 20 Communicating with the passages 30 and 34, are other passages 35 and 36 formed in the spray head, the said passages approaching each other as they extend outwardly. The jets of air and water passing through the 25 passages 35 and 36, meet at the point 37 and pass thence into the spray nozzle 15 connected with the spray head. When this fluid escapes from the nozzle, it is in the form of a fine spray delivered at the mouth or outer 30 extremity of the drill hole thus allaying or arresting the dust as heretofore explained. 35 From the foregoing description the use and operation of my improved device will be readily understood. Assuming that the drill mechanism has been put in position and the air turned on, the anchoring pin 12 will be forced in one direction and the body of the drill mechanism in the opposite direction. A 40 portion of this air will pass through the conduit 13 whence it is delivered through a passage 18 to the passage 30 and thence to a passage 35 and finally delivered to the outer extremity of the spray head 37. In the mean time the water from the conduit 27 enters 45 the passage 19 of the bolt 17 and passes thence to the passage 28 where it enters the passage 36 of the spray head whence it is delivered to the outer extremity 37 of the spray nozzle where it unites with the air and continues through the spray nozzle 15 and issues 50

therefrom in the form of a fine spray as heretofore explained.

Having thus described my invention, what I claim is:

1. The combination with a motive fluid actuated percussive tool, of a spraying device connected with the body of the tool and provided with a spray discharge nozzle protruding beyond the forward extremity of the tool body, a delivery head connected with the nozzle and provided with two passages both of which communicate at one extremity with the nozzle while their opposite extremities terminate in distinct passages, a bolt passing through said head and provided with passages which communicate with the passages formed in the delivery head, means for delivering air and water to the respective last named passages, and adjustable means for regulating the said supply of air and water. 55

2. The combination with a motive fluid actuated percussive tool, of a spraying device mounted on the tool and having a spray discharge nozzle projecting beyond the forward extremity of the body of the tool, said spraying device further comprising a spray head with which the nozzle is connected, distinct passages formed in said head and both communicating at one extremity with the nozzle, the said head being provided with oppositely disposed lateral projections having longitudinal openings with which the inner extremities of the passages in the spray head respectively communicate, regulating screws entering said openings for controlling the passage of fluid thereto, and a bolt passing through the said head at right angles to the screws, the said bolt being provided with passages communicating with the respective openings of the head, and means for supplying air and liquid to the respective passages in the bolt for the purpose set forth. 75 80 85

In testimony whereof I affix my signature in presence of two witnesses.

DANIEL S. WAUGH.
